UNITED STATES PATENT OFFICE

ALPHONSE DEMUYNCK, OF BRUSSELS, BELGIUM

INTERNAL COMBUSTION ROTARY ENGINE

Application filed June 2, 1927, Serial No. 196,078, and in Belgium June 5, 1926.

This invention relates to an internal combustion engine of the rotary-piston type, which efficiently utilizes the energy of expansion of an explosive mixture, previously compressed, and the explosion of which is produced partly in a closed chamber, and partly in the rotor body of the engine.

For this purpose the engine is essentially characterized by a rotor, which has a number of arcual cavities or expansion chambers separated by solid parts forming pistons in these arcual cavities which pistons engage with easy contact the solid sectors of a closing member, which sectors, in their turn form abutments behind the expansion chambers, to confine the gases within the prescribed limits. The expansion is obtained only by the motion of a piston under the effect of the gas pressure on its rear face.

20 The following description is made with reference to the accompanying drawings, which represent in Fig. 1 a vertical section of one motor-element according to the invention, the complete engine being constituted by the juxtaposition on the same driving-shaft of an odd number of such elements.

Fig. 2 is an axial section of a stator or casing of said element, and

25 Fig. 3 is an elevation showing means for axially reciprocating the rotary distributor valve and the inlet for the explosive mixture.

The rotor 1 is a solid disc having three arcual recesses or cavities called expansion chambers 2, extending throughout the thickness of the disc. They are separated by solid parts 3 called pistons or partitions, the profile of each of which is similar to that of an epicycloidal gear tooth.

30 This profile is determined by the single condition of obtaining an efficient closing contact with the corresponding flanks of the solid sectors of the rotary closing member 4 and no effect has to be transmitted between these contacting surfaces. Each of the pistons 3 carries two or more lateral packing strips 5 at each side, as well as peripheral packing strips upon its outer face, which afford adequate gas-tight contact with the surrounding engine casing or stator 6.

35 In order to obviate or minimize the fric-

tional wear of the rotor against the internal wall of the stator or casing 6 which might be caused by the expansion (although the stator is very efficiently cooled by a water-jacket), a small clearance may be allowed between the 55 two when the engine is at low temperature, the gas-tight closure being efficiently secured by the packing strips as stated above.

The cylindrical base of the expansion chambers is constituted by moving segments 8, extending throughout the thickness of the rotor; each of these segments has bevelled edges and is provided at the end with a lug 9 having an opening 9a. Said lug engages in a corresponding radial recess 10a with which the rotor is provided and the rotor also has a fixed pin 10 which projects into said recess and enters the opening 9a and is of slightly less diameter than said opening. The segment, when projected outwards by centrifugal force, is driven back by the rotation against it of the closing member 4 as, on the other hand, the circumferential speed of the member 4 is greater than that of the segment, the latter will be pushed in the direction of this rotative movement and be pressed against the front wall of the groove, in which it is located. The closure of the explosion-chamber will thus be perfectly secured.

70 The rotary closing member 4 is constituted by a disc of the same outside dimensions as regards diameter and thickness as the moving rotor. It has three substantially solid parts 11, called closing sectors or abutments, designed so as to engage with easy contact, the surfaces bounding the cavities 2 of the rotor 1. The profiles of the flanks of these sectors are such as to satisfy the same single condition of the rolling contact for the pistons 3 of the rotor, that is to say, said profiles 75 approximate to those of gear teeth. This condition also decides the profile of the three cavities 12 of the closing member 4, in which recesses engage the pistons 3 of the rotor 1.

80 In order to obtain equal expansions at every point, the stator or casing 6 containing the rotor 1 and closing member 4, as well as the explosion chamber 13 and the stator or casing 14a of the explosive mixture distributor is 100

cast in a single piece, the whole being enveloped in an external casing 15 containing cooling water.

The dimension of the explosion chamber

- 5 13 measured in direction parallel with the axis of the rotor 1 is less than that of the piston 3 measured in the same direction, so that at all times the packing strips will be retained in operative position on said piston.
- 10 The cooling may be obtained or controlled by means of a thermosiphon, the general intake of the water being at 16. The difference of density establishes a double current, the cold water going upwards for its greater 15 part through the compartment 16' towards the triangular canal 7 between the explosion chamber 13 and the stator of the rotating distributor, thus efficiently cooling the parts which are exposed to the greatest heating 20 action.

The heated water rises into the compartment 16'' through canals 7^a formed in the body of the stator, as shown in dotted lines in Fig. 1 and is discharged through the port 25 17 towards the radiator. The water, contained in the compartment 16''', surrounding the stator of the distributor is renewed slowly by the water coming from the triangular canal 7, so that a mean constant average 30 temperature is preserved around the distributor.

- The distributor of the explosive mixture is of a rotary type, and is constituted by a cylinder 14, turning at the same angular 35 speed as does the moving rotor 1. To this end the shaft 22 of the rotary closing member 4, which is geared with that (21) of the rotor 1 by equal gears represented in Fig. 1 by the dotted pitch circles 23, is geared with the rotating cylinder 14 by equal gears 24. The cylinder 14, has three openings 14^a for each element of the rotor, the width of which is such as to open, for a short time only, the intake aperture 18 of the explosion chamber 40 13, which time is determined by the stroke of the rotor and the moment of ignition. This distributor turns upon a fixed central cylinder 14^c, the delivering port 14^d of which is in line with the port opening into the explosion chamber 13. This arrangement of 45 double cylinders assures a perfect closure and shields the moving cylinder 14 from the pressure of the gas within the fixed cylinder 14^c. The calories absorbed by the walls of the 50 explosion chamber are distributed around the stator through conduction, this distribution being more or less controlled or affected by the mean constant temperature of the water within the waterjacket 16''' so that no irregular 55 expansion is to be feared which might cause a seizing of the distributor cylinder. In order to prevent wear of the rotary distributor cylinder, which might be caused by a deposit of carbon, the cylinder 14 may have, besides its 60 rotary movement a longitudinal reciprocating

movement of small amplitude. The rotary cylinder 14 may, for this purpose, have fast on its end an oblique groove cam 25, which engages with a pin 26 fast to the engine casing.

The inner part of the central fixed cylinder may be provided with a metallic gauze 28 to prevent the flame from passing through the distributor to the compressor.

This compressor which may be of any suitable construction will deliver volumes of gaseous mixture, varying following the speed of rotation, which variation is obtained by throttling the inlet 27, so as to obtain a sufficient pressure in the distributor for filling 80 the double explosion chamber during the short duration of the opening.

The inlet pipe communicates with the interior of the cylinder 14^c and a suitable gas-tight joint is provided between the cylinder 85 14 and the engine casing.

The distributor must be entirely closed when the edge of a piston 3 has partly opened the aperture of the explosion chamber (which is the phase indicated in Fig. 1), at which 90 juncture the sparking plug at 18 will ignite the mixture.

The complete explosion chamber is composed of the explosion chamber 13 and the space 20 of the expansion chamber comprised 95 at the moment of ignition between the respective piston 3 and the corresponding abutment of the closing member 4, which at the time have been filled with explosive mixture. The volume of these two spaces is such that 100 the gases resulting from the combustion will be able to attain an efficient degree of expansion, before the moment, at which the next following wall of the rotor will shut the proper explosion chamber 13, and before the 105 gases will exhaust through the outlet 19, which precaution is necessary in order to avoid self-ignition by the residual gases of the fresh gases which enter the explosion chamber immediately thereafter.

The action of the expanding burnt gases is utilized entirely on the back surfaces of the pistons 3, called the active surfaces to produce the driving couple rotating the driving shaft.

It results from the above considerations that the volume of each charge of the explosive mixture which is to be admitted is comparatively small about 70 c. cms. at the usual expansion ratio for a rotor of 18 cm. diameter, and an expansion chamber 6 cm. wide and 4 cm. deep.

The cycle of operation of the motor is as follows: When the port of the rotating distributing device 14 comes in front of the port of the conduit 13, the compressed gas which had been compressed before by a compressor and is fed by the said conduit, enters and fills the chamber 13 and the space 20 which forms the explosion chamber. The distributing de- 120 125 130

vice, in continuing its rotative movement, then closes the opening of the conduit 13. At this instant the spark plug ignites the explosive mixture, and the resultant expansion following the explosion causes the piston 3 to be shifted, which will turn with it the motor shaft, until the said piston has passed over the exhaust opening 19 through which the burned gases are discharged, and until the following partition of the rotor has arrived and closes the explosion chamber 13. Said chamber is again filled with explosion gas through the ports of the distributing device 14, which successively register with the port 14^d and chamber 13 and thus the cycle is repeated for each expansion chamber.

In order to obtain a practically constant turning moment, it will be advantageous to employ a number of the elements described above by juxtaposing them on the same driving shaft, each element having preferably a separate stator element such as is shown in Fig. 2. These elements, after adjustment, are assembled with interposed locating rings or segments 29 which ensure an efficient jointing and centering of adjacent elements, and are finally fixed together by tie rods and nuts.

The number of the expansion chambers 2 for each rotor element 1 is given by way of example, and may be reduced to two or increased to four, according to the diameters adopted, and the quantities of the explosive mixture which it is desired to be admitted for each explosion.

35 The closing member 4 and the distributing cylinder 14 will be correspondingly modified.

What I do claim as my invention, and desire to secure by Letters Patent is:

In an internal combustion engine of the rotary piston type, a rotary closing member having peripheral recesses, a rotor having pistons arranged to engage in said recesses and also having recesses in its periphery between the bases of said pistons, the side walls of each recess being parallel, said rotor also having radial recesses in its ends which are midway between said side walls of said peripheral recesses, segments in said peripheral recesses of the rotor arranged to engage the periphery of the closing member and movable radially with respect to the rotor and also tangentially, the sides of each segment being parallel and corresponding with those of said recesses, said segments having radial lugs at their ends arranged in said radial recesses of the rotor, said rotor having pivots by which said lugs are mounted in said radial grooves for slight radial and tangential movement of said segments.

60 In witness whereof I affix my signature.
ALPHONSE DEMUYNCK.
